DESIGN FOR A PICTURE FRAME

William P. Campbell, Los Angeles, Calif.

Application April 23, 1945, Serial No. 119,148

Term of patent 3½ years

(Cl. D29—20)

To all whom it may concern:

Be it known that I, William P. Campbell, a citizen of the United States of America, residing in Los Angeles, county of Los Angeles and State of California, have invented a new, original, and ornamental Design for Picture Frames, of which the following is a specification, references being had to the accompanying drawing, forming a part thereof.

Fig. 1 is top plan view of a picture frame showing my new design.

Fig. 2 is a front elevational view of the picture frame, and

Fig. 3 is a side elevational view.

I claim as my invention:

The ornamental design for a picture frame, as shown.

WILLIAM P. CAMPBELL.
